GEORG HEINRICH SCHIEFERSTEIN, OF BERLIN-CHARLOTTENBURG, GERMANY

METHOD AND MEANS FOR SUPERVISING RAILROADS

Application filed August 20, 1927, Serial No. 214,346, and in Germany August 20, 1926.

This invention relates to a method of supervising the condition of railway tracks.

As is evidenced by the frequency of accidents and collisions, the supervision of 5 railway tracks as now carried out with known means, is imperfect.

The subject of the present invention is a method of testing railway tracks from a distance, by the aid of mechanical oscillations 10 induced in the rails themselves.

Considered from the oscillometric standpoint, lines of rail always possess elasticity and mass in such degree that they may generally be regarded as excellent conductors of 15 oscillations of any order of dimensions. If, therefore, a line of rail be excited with, say 30000 oscillations per minute by a mechanical system oscillating with that frequency, the line of rail in question will transmit this 20 oscillation through a longer or shorter distance, depending on the input of energy, each fishplate joint, however, exerting a certain damping effect on the oscillation transmitted.

It may therefore be assumed that, in the 25 case of lines of rail of normal character, a perfectly definite proportion of the input energy will be destroyed by damping, per kilometer or 10 kilometers. When this value has once been determined by repeated measurements, which are easily carried out, it may naturally be concluded, when fresh tests reveal substantially increased losses, that the rail joints in the section under examination have correspondingly deteriorated, either in 30 general, or in some particular spot; or, if the emitted oscillations disappear completely, that there is some break in the line of rail.

According to this novel perception, on which the present invention is based, all that 40 is necessary, in order to be able to form an estimate of the mechanical condition of a railway track, is to impart to the track, at any convenient point and by known means, mechanical oscillations lying within the range 45 of audibility, and to receive said oscillations at a distant point, which may be, if desired, translated into electrical energy, also by known means, such as a telephone, microphone, relays or recording instruments and 50 to note the variations in the intensity of the

sound, or the amount of energy absorbed. The sensitiveness of the receiving device (which may be equipped with amplifiers of known type) on the one hand, and the possibility of employing, on the other, an energy 55 of one kilowatt or more without risk, enables the range of distance to be selected to suit working conditions.

That such a system of supervision must afford, in the first place, a constantly definite 60 idea as to the condition of the rail joints in the intervening section, and secondly, a manifest record at the receiving station, in the event, say, of a rupture in the continuity of the line through the failure of even a single 65 fishplate (which can be detected in known manner by signals) should be directly evident, since the energy of excitation and the sensitiveness of the receiver can be maintained at constant value in each case, and the 70 relatively low damping at each joint rises to infinity when the fishplate becomes detached.

It may even be assumed, and can be tested with sufficient frequency in the case of joints at normal distances, that the detaching of a 75 fishplate (which is always a matter of several minutes) can be clearly followed and recognized in the acoustic receiver, so that at the moment danger arises suitable measures can be immediately taken.

In the case of short distances, the acoustic signals can be detected with correspondingly simple means, and even by means of headphones, in known manner.

It might be advantageous to check a section with, for example, 30000 oscillations from A, and 40000 oscillations from B. Both oscillations can be differentiated by signalling means, or acoustically by sound filters, mono- 85 telephones or other known devices.

Since the present arrangement reacts to acoustic excitation of the rail track, the sound due to a train travelling in the section in question must also be determinable in the receiving apparatus, such sound superimposing itself on the relatively high and pure sinusoidal note. Hence the approximate position of the travelling train can also be estimated from a distance, and its presence on the section determined.

The excitation of the mechanical oscillations may be effected in known manner, both electrically, by means of a magnetic loose-coupling, and mechanically by the use of one of the known types of mechanical couplings (elastic coupling, inertia coupling, friction coupling, intermittent coupling).

In so far as possible, acoustic receivers are used, the range of oscillations employed may 10 extend right through the acoustic scale, but it is also possible to operate with oscillations to which the ear is not directly sensitive, i. e. supersonic.

When work is being carried out on the 15 track, the mechanical oscillation continuously transmitted through the line of rail can be utilized for directly supervising the work performed, especially the efficiency of the joints. In this case also, an oncoming train 20 can be detected, and the necessary operations be arranged accordingly.

In order that the invention may be fully understood it will now be described with reference to the accompanying drawings, in 25 which—

Figure 1 represents the typical arrangement of a generator for initiating mechanical oscillations by mechanical means.

Fig. 2 shows a typical construction of the 30 mechanical exciting member of such a generator.

Fig. 3 shows an arrangement of an apparatus for receiving the mechanical oscillations transmitted by a line of rail.

35 In Fig. 1, 1 denotes a railway rail which is connected to the adjoining rail by a fish-plate 2. The excitation of the line of rail is effected by setting a generator 6 (composed in known manner of an elastic member 4 rigidly connected to a mass 5 capable of oscillating) in oscillation at high frequency and small amplitude, said oscillations being transmitted to the rails by the mass 3 to which the member or tube 4 is also rigidly connected. The frequency may be such as lies within the audible range appreciable by the human ear, or it may be higher than such range, so that it can only be received or recorded by suitable receiving apparatus in known manner.

50 Fig. 2 represents a typical embodiment of the oscillation generator. Rotary unbalanced members 6 are rotated at a speed corresponding to the periodicity of the oscillatory system 4, 5, by means of a motor 14, through belt transmission gear 11, 12 and 13, and with the interposition of an elastic member such as a spring 8 which connects the driving and driven portions. The excentrically loaded or unbalanced wheels 6 cause their 55 shaft section to vibrate, and this vibration is imparted to the mass 5 which sets up vibration in the elastic or resilient member 4 that transmits vibrations to the mass 3 rigidly connected to the rails 1. The connecting member 4 is 60 yielding to variation in amplitude between the 65

rails and the generator of the mechanical oscillations.

Figure 3 shown an arrangement for receiving the oscillations at a distant point. The mechanical oscillations imparted to the rail 1 are transmitted through the fishplate 2 to the adjoining rail, and thence to the next, and so on, and, as the result of the damping effect of each pair of fishplates, are weakened to a certain extent, which increases in proportion 70 as the jointing is less effectively carried out. 75

A microphone 16, which translates the mechanical impulses into electrical impulses, is attached to the line of rail by means of an angle bracket 15 and can also be loaded with 80 a mass 17, enables a percentage of the oscillation energy to be received, translated into electrical energy, and transmitted through a conductor 18 to a telephone receiver 20, which may also be provided with a local amplifier 85 19 of electrical current in known manner.

The receiving apparatus employed may be of any suitable type adapted to receive minute electrical impulses, which will induce the person in charge to set the section of track out of operation; alternately, the receiving apparatus may be arranged to operate through relay devices in order to block the section in question automatically. 90

I claim—

1. A method of supervising the condition of railway tracks, which consists in exciting the line of rail at certain points, by means of generators, with mechanical oscillations of relatively high frequency and low amplitude, which are transmitted through the line of rail itself, and receiving said oscillations at any convenient point by suitable receiving apparatus, thereby obtaining information regarding the condition of the line of 100 rail transmitting said oscillations. 105

2. A method of supervising the conditions of a line of rails of a railway track, which comprises setting the line of rails in mechanical oscillation of high frequency and small amplitude, receiving said oscillations at a 110 distant point of the line of rail, and translating such received oscillations into electric impulses of audible frequency.

3. A method of supervising the conditions 115 of a line of rails of a railway track, which comprises setting the line of rails in mechanical oscillation of high frequency and low amplitude, the amplitude of the oscillations being reduced from one rail to another by the rail connections, receiving at a distant point mechanical oscillations, translating such mechanical oscillations into electrical impulses and amplifying said impulses. 120

4. Method as set forth in claim 1, in which the damping effect exerted by the individual rail connections or joints on the mechanical oscillations transmitted therethrough changes the audibility in accordance with the efficiency and condition of the connec- 125 130

tion or joint or of a number or all of the series of joints, and determines the condition of the line of rail, whereby supervision and control is enabled.

5. A method of supervising railway track, which comprises generating mechanical vibrations in a line of rail thereof at one point of said line, and at a distant point of said line of rail listening to the sound produced by such vibrations, and therefrom determining the efficiency of the joints of the rails in the line of rail between the two points.

10 6. A device for supervising the condition of railway tracks, consisting of a generator of mechanical oscillations attached to a rail of the section under supervision, and one or more receivers for such oscillations connected to the line of rail at one or more points remote from the generator for receiving the mechanical oscillations transmitted through the line of rail from the generator.

15 7. Mechanism for supervising the condition of railway track which comprises, a mass rigidly connected to a rail, a resilient member rigidly connected to the mass, and means for setting the member in vibration, and means at a distant point of the rail to receive the vibrations set up in the rail.

20 8. Mechanism for supervising the condition of railway track, which comprises a mass rigidly connected to a rail of such track, a member connected at one end to said mass and capable of oscillation, and means on the other end of said member to set it in oscillation and operating in resonance therewith, and means at a distant point of the line of rail to receive oscillations set up therein.

In testimony whereof I affix my signature.
